APPARATUS FOR TAKING FLUID SAMPLES

Ben E. Lindsly, Washington, D. C.

Application May 28, 1935, Serial No. 23,903

11 Claims. (Cl. 166—19)

This invention relates to a method and apparatus for obtaining samples from which physical and chemical characteristics of a fluid are ascertained as the fluid exists in a natural reservoir. For example, it is desirable to possess data regarding condition of oil contained in an oil producing formation, such as the quantity of gas liberated from solution upon diminution of pressure, the relative volumetric proportions of gas to oil at various pressures throughout the length of flow string in a well drilled into the formation, and other similar data wherewith it is possible to predict physical changes that oil and gas mixtures may undergo throughout the life of the oil pool. The possession of such information also makes it possible to more efficiently design well flowing equipment.

Heretofore it has been difficult to obtain samples which actually represent subsurface mixtures of oil and gas for the reason that such samples are taken at different pressures and temperatures than those actually existing in the producing formation. Also, the oil contained in such samples has been intermingled with extraneous gas, i. e., gas which either was in solution originally or was liberated from solution at some higher pressure and later became mixed with the original undissolved gas.

It is obvious that such samples might have their gas content either increased or decreased from the amount of oil contained in the producing formation and the data obtained therefrom is not conclusive.

In other words, the oil when it actually existed in the formation might have been unsaturated so that it absorbed additional gas by the time the sample was taken. Upon analysis, such sample would liberate more gas per unit volume of oil than the oil originally contained. On the other hand, if the oil in the original reservoir were completely saturated with gas, reduction of pressure and change in temperature at the place where the sample was taken would result in gas liberation so that the sample contains less gas per unit volume of oil than was originally contained in an equal volume in the reservoir.

It is, therefore, the principal object of the present invention to provide for taking samples of the fluid directly at the bottom of the well and at substantially the temperature and pressure conditions carried within the producing formation.

In accomplishing this and other objects of the invention, as hereinafter pointed out, I have provided improved details of structure, the preferred

forms of which are illustrated in the accompanying drawings, wherein:

Fig. 1 is a vertical section through a well in which is illustrated a sampling apparatus embodying the features of the present invention.

Fig. 2 is a similar but enlarged view showing the sampling apparatus in vertical section and showing the trapping valves in open position to admit oil to the collecting chamber of the apparatus.

Fig. 3 is a similar view but showing the valves in closed position to trap a sample of the oil in the collection chamber.

Fig. 4 is a vertical section through the apparatus in inverted position and equipped with a laboratory head wherethrough the sample is removed to a testing bomb.

Fig. 5 is an enlarged section through the head of the apparatus particularly illustrating the method of admitting the pressure fluid and timing outlet of the fluid to control operation of the upper trapping valve.

Fig. 6 is a horizontal section on the line 6—6, Fig. 5.

Fig. 7 is a horizontal section on the line 7—7, Fig. 2.

Fig. 8 is a horizontal section through the laboratory head on the line 8—8, Fig. 4.

Fig. 9 is a detail fragmentary section of the container barrel particularly illustrating the lower trapping valve and its seat.

Fig. 10 is a detail perspective view of the spider used in unseating the upper valve when the sample is to be transferred to the testing bomb.

Fig. 11 is a vertical section through a well hole similar to Fig. 2 illustrating a sectional view of a modified form of the invention.

Referring more in detail to the drawings:

1 designates a sampling device that is lowered through a well hole 2 by means of a cable 3 to a point adjacent the bottom of the well for taking a sample of the fluid flowing from the oil producing strata into the well hole. The sampling device includes a tubular section 4 of suitable diameter to be freely lowered through the well hole or a flow stream, and of sufficient length to provide a collection chamber 5 having sufficient capacity to contain a sample of desired quantity.

Fixed to the lower end of the tubular section is a nipple 6 having threaded ends 7 and 8 for respectively engaging the internal threads 9 in the lower end of the tube and internal threads 10 of a coupling 11 having its lower end terminating in depending ears 12 and 13 located at opposite sides of a fluid inlet slot 14. The

ears 12 and 13 are provided with apertures 15 and 16 through which a bolt 17 is passed for connecting a temperature and pressure recording device indicated at 18, Fig. 1. The device 18 may 5 be any one of a number of conventional devices now on the market and specifically forms no part of the present invention.

The well fluid enters the coupling 11 through the slot 14 and is apt to carry with it quantities 10 of sand or other material that might tend to keep the valves from seating. To prevent entrance of sand with the oil into the flow channel 19 of the nipple 6, a plurality of spaced screens 20 are inserted in the coupling 11 below the threaded end 15 8 of the nipple so that the oil must flow through the screens before it can enter within the nipple 6.

Extending across the upper end of the nipple is a spider 21 provided with an axial opening 22 20 to form a guide for a valve stem 23. Secured to the upper end of the valve stem is a back check valve 24 having a depending annular rib 25 for sealingly engaging against a seating ring 26 that is carried by the upper end of the nipple to trap 25 a sample of well fluid in the collection chamber when the valve is closed by gravity as presently described.

The valve 24 remains seated by reason of gravity and opens in response to flow of fluid through 30 the ports 27 of the spider to admit the fluid into the collection chamber 5. To limit upward movement of the valve, the lower end of the stem carries a stop 28 that engages against the lower face of the spider.

35 In order to seal the threaded connections of the nipple with the lower end of the tubular section and coupling 11, the nipple is provided with an annular collar 29 to form upper and lower annular shoulders 30 and 31 to seat gasket rings 40 32 and 33 that engage against the ends of the tubing section and coupling respectively.

A similar nipple 34 is threaded into the upper end of the tubing section and carries a spider 35 and valve seating ring 36 on its lower end identi- 45 cal to the spider and seating ring carried by the lower nipple to form a guide for a valve rod 37 and a seat for a valve 38 carried on the lower end of the rod and whereby flow of fluid from the collection chamber to the check chamber is 50 stopped to retain a sample of the fluid in the collection chamber under the conditions presently described.

The valve rod 37 projects upwardly through the bore of the nipple 34 and is connected with an 55 operating mechanism which is reciprocably mounted in a tubular guide section 39. The tubular guide section conforms in diameter to the tubing section 4 and has its lower end threaded on the upper end of the nipple 34, as best il- 60 lustrated in Fig. 2. The upper end of the guide section carries a head 40 having a reduced neck 41 on its lower end that is threaded into the upper end of the guide section. Fixed to the upper end of the head is a loop 43 having an eye 65 to which the cable 3 is connected.

Located within the lower end of the guide section is a horizontal partition 44 spaced from the upper end of the nipple 34 to form the bottom of guide and check chambers 45 and 61 that prevent sudden closing of the valve 38 incidental to flow of well fluid through the upper end of the tubular section to a plurality of outlet ports 48 that are formed in the guide section at a point below the partition 44, the total area of the outlet 75 ports 48 being such as to permit free flow of oil

there-through to facilitate the complete purging of collection chamber 5, during this process of bobbing later described.

With the construction thus far described, oil flows through the inlet slot 14, screen 20, through the ports of the spider 21, past the lower valve into the collection chamber and out of the collection chamber past the valve 38 through the ports of the spider 35 into the check chamber and out through the ports 48 while the device is 10 being lowered into the well.

Upon suspending the lowering operation of the device, the lower valve will seat under gravity but means must be provided for seating the upper valve to trap a sample of fluid within the collection chamber.

In the preferred form of the invention, this is accomplished by means of a coil spring 49 housed within the guide section and having one end bearing against the partition 44 and its opposite end 20 against the follower plate 50 of a cup-shaped piston 51 under response to flow of a pressure fluid 52, that has been injected into the guide section through the head 40, as now to be described.

Threaded into a recess 53 extending radially within the head 40 is a check fitting 54 having a port 55 normally closed by a back check valve 56 that is normally retained seated by means of a spring 57. The outer end 58 of the fitting is shaped to accommodate a conventional type high pressure grease gun for delivering grease or other pressure medium past the valve and through a channel 59 which conveys the fluid through a nozzle 60 into the chamber 61 that is formed between the head and the piston 51 to force the piston downwardly against pressure of the spring 49 which causes the valve stem 37 to unseat the valve 38.

The head 40 is also provided with an outlet 40 channel 62 which communicates with a restricted port 63 in a plug 64 threaded into a recess 65 in the side of the head 40 opposite the inlet 50 and having an enlarged outer portion adapted to receive the head 66 of a needle valve 45 67 having a tapered end 68 adapted to fit the seat 69 at the outer end of port 63 to prevent escape of grease from the check valve when the needle valve is in place.

The inlet of the channel 62 is covered by a 50 screen 70 that is carried by a plug 71 threaded into the recess 72 of the head and having a bore communicating with the channel, the purpose of the screen 70 being to prevent material from the chamber from entering the channel that might 55 tend to clog the outlet port 63, through which the grease is discharged under the propelling influence of the piston actuated by the spring 49 when the needle valve 67 is removed. Since the port 63 is of fixed size, the rate of grease flow 60 is constant and provides for timing closure of the valve 38.

In order to protect the inlet fitting and port 63, the upper portion of the head is of reduced diameter to loosely mount a guard ring 74 having its lower end attached to a shoulder 75, the inner diameter of the ring being such as to provide ample space between the ring and the reduced portion of the head 40 for the outlet of grease when the needle valve 67 has been, re- 70 moved.

In using an apparatus constructed and assembled as described, the pressure and temperature recording device is run into the well to determine the actual pressure and temperature conditions 75

at the bottom of the well and from this pressure and temperature is calculated the size of the port 63 to give the desired time closing of the upper valve. A plug 64 having the required orifice is 5 then screwed into the recess, after which the needle valve 67 is threaded into the plug to close the port 63 while grease is being injected through the inlet fitting into the chamber 61.

The amount of grease injected is preferably 10 such as to effect compression of the spring about two and one-half inches; the amount of grease admitted, of course, depending upon its viscosity and the depth of the well or the point at which the sample is to be taken, the idea being that the 15 grease flow through the port 63 will provide ample time for the device to be run into the well, flushed of well fluid and a sample of oil admitted to the collection chamber before sufficient amount of 20 grease has been extruded to permit closure of the upper valve.

In usual practice, it requires about thirty-four 25 minutes at a temperature of 132° F. to expel grease from the chamber 61 and, therefore, the sampling operation is planned so that the desired sample will be in the collection chamber 30 within thirty-four minutes after removal of the needle valve. Usually, however, the time required to close the upper valve is greater than the calculated thirty-four minutes for the reason that it 35 takes at least twenty minutes for the sampling device and the oil in the cylinder to approximately assume the bottom hole temperatures. The grease, therefore, remains in viscous condition for a longer period and the closing period of the valve is longer than that calculated.

After the grease has been injected, the needle valve is inserted to prevent extrusion of the grease under the action of the spring 49. The 40 temperature and pressure recording device 18 is then secured to the bolt 17 by means of a wire 16 as shown in Fig. 1, or preferably by inserting bolt 17 through the hole in the head of device 18, which has previously been drilled and shaped to fit between ears 12 and 13, and the lowering cable 45 is attached to the eye of the loop 43.

As soon as the device is ready to be lowered into the well, the needle valve for closing the orifice 63 is removed and the guard 14 positioned over the reduced portion of head 40 to prevent 50 entrance of foreign matter that might tend to clog the outlet of the orifice. The device is then lowered into the well to the bottom thereof, or to the point at which the sample is to be taken.

During lowering of the device, the liquid standing in the well enters through the slot 14, lifting the lower valve and moving past the upper valve for flow out through the ports 48 so that there is a constant movement of liquid therethrough. During the lowering of the device, the spring 55 49 is gradually expanded to extrude the grease but at the time the device has reached the bottom of the hole, however, there is still sufficient grease remaining to hold the valve in open position for a sufficient length of time to obtain an 60 actual sample within the collection chamber.

In order to overcome uncertainties of obtaining 65 a true sample, it is good practice to allow the sampling device to remain in the bottom of the well a sufficient length of time to permit it to take on the temperature of the fluid issuing from the formation.

When the device reaches the bottom of the well it is raised and lowered a number of times to purge the collection chamber of well fluid 70 received thereinto during lowering of the device 75

through the well. While bobbing the sampling device, the down stroke should be made as rapidly as possible so that the impact on the lower valve will open it and cause bottom hole oil to enter the collection chamber and expel the other 5 oil through the upper valves and ports. After the sample has been taken and it is assured that the upper valve is closed, the device is withdrawn from the well.

After removal of the device from the well the 10 coupling 14 is removed from the nipple 6 and the spider 11 (Fig. 10) is inserted in the open end of the nipple, as shown in Fig. 4. The spider includes a cylindrical body portion 78 having depending legs 79 and 80 spaced apart to straddle 15 the stem of the valve 24, the legs 79 and 80 being of suitable dimensions to pass through the ports of the spider and engage against the face of the valve.

A laboratory head 81 is then screwed onto the 20 nipple so that an end 82 thereof sealingly engages with the gasket on the nipple. The laboratory head is provided with a central bore 83 threaded at its lower end to mount a screw 84 having a cone-shaped point on its lower end adapted to 25 seat in a cone-shaped recess 85 on the body portion of the spider. The opposite end of the bore is formed to receive a suitable pack'ng ring 86 and gland 87 for sealing the upper end of the screw. The projecting end of the screw 84 is of 30 polygonal shape to accommodate a wrench whereby the screw is rotated and screwed against the spider to cause opening of the valve 24.

The head 81 has spaced channels 88 and 89, 35 communicating at their inner ends with the interior of the nipple and at their outer ends respectively with a source of fluid pressure medium, such as mercury, and with a testing bomb 90 through tubings 91 and 92. All of the air in head 81, channels 88 and 89, bomb 90 and connection tubes 91 and 92, is completely displaced by filling these spaces with mercury, or other suitable medium.

It is thus apparent that when the valve 24 is 40 opened, communication is established with the 45 interior of the collection chamber and the interior of the testing bomb and with the source of fluid pressure medium. The mercury or other suitable liquid which will not mix with the sample of well fluid is then pumped under the required 50 pressure through the channel 88 into the collection chamber to displace the sample therefrom, which flows out through the channel 89, tubing 92 and by proper manipulation of valves 55 displaces the mercury which had previously been placed in the testing bomb.

When the testing bomb is being filled, the mercury and the bomb are maintained at an equal or somewhat higher pressure than the pressure determined by the measuring device 18. When 60 oil has displaced all of the mercury from the bomb, valves 93, 93a, and 93b are then closed to retain the remaining oil in chamber 5 and to entrap the sample of oil in the testing bomb. The testing bomb is then disconnected from the laboratory head and the sample contained therein may, by simple manipulation of valves, and subjection to a constant temperature bath, be brought to the same pressure and temperature conditions and thereby become identical in chemical and 70 physical characteristics as when in the producing formation.

The sample is then tested to determine the physical and chemical characteristics of the oil.

In the modified form of the device (Fig. 11) 75

a dash pot 95 of conventional form is located in the check chamber within the guide section 96 corresponding to guide section 39 of the preferred form of the device. Fixed to and extending upwardly from the dash pot is a rod 97 which terminates below a packing nut 98 that divides the check chamber into upper and lower portions 99 and 100, the lower of which is provided with vent ports 101 through which fluid in the check chamber may escape to the well. The upper end of the rod 97 carries a collar 103 adapted for supporting a trip rod 104 which is slidable in packing nut 98 and provided at its upper end with a collar 105 forming a seat 106 for the arm 107 of a bell crank lever 108. Bell crank 108 is pivotally mounted on a bracket 109 attached to the inner face of the guide section within the upper portion of the check chamber and has a second arm 110 extending substantially horizontally within the upper portions of the check chamber. Surrounding rod 97 within the lower portion 101 of the check chamber and bearing at its lower end against a plug 111 in said chamber and at its upper end against the collar 103 on said rod is an expansion spring 112 adapted to urge the rod upwardly and hold the arm 107 of the bell crank lever to its seat on collar 105. Spring 112 is held compressed and the valve 38 open to permit passage of well fluid through the collection and check chambers to exit through the outlet ports in the guide section. When the collection chamber has been purged preparatory to receiving a sample, the stop valve 38 is moved to its seat to close the collection chamber by unseating of the bell crank lever from its engagement with collar 105 so that the spring 112 may lift the rod 97 and stem 37 of valve 38 through thrust of a rod 114, slidably mounted in a channel 115 in a head member 113 carried by the guide section, under impact of a go-devil 116 which is slidably mounted on the cable whereby the device is suspended in the well.

What I claim and desire to secure by Letters Patent is:

1. Apparatus for taking samples of fluid from a well including a collection chamber having inlet and outlet ports, a trap valve for preventing back flow from said chamber through the port, a stop valve controlling outlet of fluid from the chamber through the outlet port, means for closing the stop valve, and means for retarding closing movement of the stop valve.

2. Apparatus for taking samples of fluid from a well including a collection chamber having inlet and outlet ports, a trap valve for preventing back flow from said chamber through the inlet port, a stop valve controlling flow of fluid through the chamber and outlet port, means for closing the stop valve, and means for confining a body of fluid in restraining relation to said closing means to retain the stop valve open, including a bleeding port through which said fluid may escape in restricted flow to permit closing of the stop valve.

3. Apparatus for taking samples of fluid from a well including a collection chamber having inlet and outlet ports, a back check valve for the inlet port, a stop valve for the outlet port, means yieldingly urging the stop valve to closed position, means for closing the valve, means for effecting application of pressure to said closing means to resist closing of the valve, and means for releasing the pressure means to permit closing of the valve.

4. Apparatus for taking samples of fluid from a well including a collection chamber and having inlet and outlet ports, a back check valve for the inlet port, a stop valve for the outlet port, means for closing the stop valve, and means for confining fluid pressure medium in retarding relation to said closing means including an outlet for release of said pressure medium in restricted flow to permit slow closing of the valve.

5. Apparatus for taking samples of fluid from a well including a chamber having inlet and outlet ports, a back check valve for the inlet port, a stop valve for the outlet port, a fluid check chamber, yielding means urging the stop valve to closed position responsive to pressure of fluid in said chamber for retaining the stop valve in open position, and means permitting retarded outlet of fluid from said chamber to permit corresponding slow closing movement of the outlet valve in response to diminution of volume of fluid in said chamber.

6. A sampling device of the character described including a tubular body member enclosing a sample fluid collecting chamber provided with inlet and outlet ports and a check chamber connected with the collecting chamber, a check valve for said inlet port, a stop valve controlling flow of fluid between said chambers, a piston in the check chamber, means connecting the piston with said stop valve, a spring for moving the piston in one direction, means for supplying fluid pressure medium to the check chamber to shift the piston against the tension of said spring, and an orifice member for permitting release of said fluid pressure medium to effect slow closing movement of the stop valve under tension of said spring.

7. A sampling device of the character described including a sample fluid collecting chamber having inlet and outlet ports and a check chamber connected with the collecting chamber through said outlet chamber, a check valve for the inlet port, a stop valve for the outlet port, a piston in the check chamber, a rod connecting the piston with the stop valve, a spring urging the stop valve to closed position, and means for introducing pressure medium into said check chamber to act against the piston for retaining the stop valve in open position against the tension of said spring, the check chamber having restricted outlet for releasing pressure medium from the check chamber in restricted flow to permit closing of the stop valve by said spring.

8. In apparatus for taking samples of fluid from a well, a hollow barrel including separate collecting and check chambers and vent openings between the chambers, inlet and outlet ports permitting flow through the collecting chamber to said vent ports, a back check valve for said inlet port, a stop valve for said outlet port responsive to pressure of fluid in the check chamber for opening the outlet port, means for bleeding the check chamber of fluid, and yielding means responsive to pressure of said fluid to permit the stop valve to open and for gradually seating the stop valve against diminishing pressure of said fluid.

9. Apparatus for taking samples of fluid from a well including a collecting chamber having inlet and outlet ports permitting flushing flow of well fluid through said chamber, a check valve for the inlet port, a stop valve for the outlet port, a piston in the check chamber connected with said stop valve, means for supplying pressure medium to the check chamber to move the

piston in one direction in response to supply of pressure fluid to the check chamber to unseat the stop valve, means for releasing pressure medium from the check member to permit movement of the piston in the opposite direction to close the valve, and yielding means resisting movement of the piston to open the valve and urging the piston to close the valve.

10. Apparatus for taking a sample of fluid from a well including a collecting chamber having a port for admitting fluid from the well and an outlet port, a check chamber having a bleeding port and an intermediate vent chamber adapted to receive well fluid through said outlet port and having a vent opening, a check valve for said inlet port, a valve for said outlet port, a piston in the check chamber connected with the outlet valve, and a spring urging the piston to close the out-

let valve against diminishing volume of pressure fluid escaping from the check chamber through said bleeding port.

11. Apparatus for taking a sample of fluid from a well including a collecting chamber having inlet and outlet ports, a check chamber having a bleeding port and an intermediate vent chamber connected with the collecting chamber through said outlet port and having a vent opening, a back check valve for said outlet port, a piston in the check chamber, a rod connecting the piston and outlet valve, and a spring engaging the piston, yieldable under pressure of fluid supplied to the check chamber to permit the outlet valve to open and expansible under diminishing pressure of fluid exhausting from said chamber to gradually close the valve.

BEN E. LINDSLY.
